SAFETY RAZOR

Archie H. Lyons, Modesto, Calif.

Application January 29, 1945, Serial No. 575,075

4 Claims. (Cl. 30—72)

This invention relates in general to an improved safety razor of the type which includes a pair of cooperating head members adapted to clamp a double edged razor blade therebetween; the head members being detachably secured together by a central threaded stud on one member projecting through the other member, and on which stud the handle is screwed, whereby to maintain said head members in clamping engagement with the blade.

It has been found in practice that if the handle of the above type of safety razor is adjusted so that such handle is not fully advanced and so that the head members are not clamped together as tightly as possible, the double edged blade between such head members will shave the face much closer. This is for the reason that the blade, which is bowed between the head members, has a lesser bow imparted thereto than would be the case if said head members were fully clamped, and as a result the relative cutting angle of the blade is increased, which produces a closer shave.

However, the handle when so adjusted frequently fails to stay in place and loosens. It is therefore an object of this invention to provide, in a razor of the type described, manually controlled locking means between the turnable handle and adjacent head member whereby the handle of the razor assembly can be locked in any selected position of adjustment.

A further object of this invention is to provide a safety razor assembly, as in the preceding paragraph, in which said locking means comprises a slidably mounted pin on the handle, a row of pin receiving sockets formed in the adjacent head member concentric to the stud, and a hand actuated element on the handle adapted to control advancing or retraction of said pin relative to said row of sockets.

A further object of the invention is to provide a simple and inexpensive device, and yet one which will be exceedingly effective for the purpose for which it is designed.

These objects I accomplish by means of such structure and relative arrangement of parts as will fully appear by a perusal of the following specification and claims.

In the drawing:

Figure 1 is a sectional elevation, enlarged, of a safety razor embodying the present invention.

Figure 2 is a plan view of the razor with the handle detached, showing the concentric row of pin receiving sockets as formed in the top head member.

Referring now more particularly to the char-

acters of reference on the drawing, the razor is generally of conventional type and includes a bottom head member 1 having a top head member 2; the top head member having, along opposite edges thereof, rows of spaced guard teeth 3, said teeth projecting laterally outwardly beyond the corresponding edge of the bottom head member 1. A central, threaded stud 4 is formed on the bottom member 1 and projects through a corresponding opening 5 in the top head member 2; the stud extending some distance beyond said head member 2.

An elongated handle 6 is formed at its lower end with an axially opening tapped bore 7 into which the stud 4 is adapted to be screwed. When the handle is screwed onto the stud 4 it engages with the top surface of head member 2 and urges the latter toward the bottom head member 1. A double edged blade 8 engaged over the stud 4 is thus clamped between said members.

It will be seen that if the handle 6 is not run down against the head member 2 as far as possible, the blade 8 will not be clamped between said head members as tightly as would otherwise be possible. The blade, which is normally bowed between said members on account of adjacent convexo-concavo faces, thus has a lesser bow imparted thereto, which increases the cutting angle between the sharpened opposite edges of the blade 8 and the adjacent guard teeth 3, which produces a closer shave.

However, it is sometimes difficult to use a safety razor with the handle 6 set in a position of adjustment less than full advance, for the reason that the handle tends to loosen and back off from the adjusted position. To prevent this I provide the following locking mechanism, and which is the essence of the present invention:

The handle 6 is formed with a longitudinal bore 9 therethrough from end to end, said bore having an elongated pin 10 slidably therein, the lower end of the pin being rounded and adapted to seat, selectively, in any one of a circular row of sockets 11 formed in the upper surface of the top head member 2 in concentric relation about the stud 4.

The upper end portion of the pin 10 is enlarged to form a plunger 12. The bore 9 is enlarged to slidably receive said plunger 12 with the enlargement extending some distance below the lower end of the plunger. A loaded compression spring 13 surrounds the pin 10 between the plunger 12 and a shoulder 14 at the lower end of the enlarged portion of the bore 9. The spring 13 tends to retract the pin 10 from the sockets 11.

At its upper end the plunger 12 is rounded, as at 15, and extends out of the corresponding end of the handle 6, there being a screw cap 16 threaded on the upper end of said handle and engaging the rounded upper end 15 of the plunger 12.

It will be seen that the screw cap 16 may be rotated in one direction or the other to cause advance or retraction of the pin 10 relative to the sockets 11.

When the razor is being assembled for use the cap 16 is unscrewed to such point that the pin 10 does not project below the lower end of the handle. The razor is then assembled, and the handle screwed onto the stud 4 to the extent desired. Thereafter the cap 16 is screwed down so as to advance the pin 10 into the adjacent one of the sockets 11, which thus effectively locks the handle 6 against rotation. With the handle thus locked in position the razor assembly is maintained with the blade 8 set at the desired cutting angle.

From the foregoing description it will be readily seen that there has been produced such a device as substantially fulfills the objects of the invention as set forth herein.

While this specification sets forth in detail the present and preferred construction of the device, still in practice such deviations from such detail will be resorted to as do not form a departure from the spirit of the invention, as defined by the appended claims.

Having thus described the invention, the following is claimed as new and useful and upon which Letters Patent is desired:

1. A safety razor comprising a pair of cooperating head members adapted to clamp a double-edged blade therebetween, a central, threaded stud on one member projecting through the other member, a handle screwed onto said stud whereby to secure said members together and clampingly engage the blade therebetween, and means to re-

leasably lock the handle against unscrewing from the stud; said locking means comprising a pin slidably mounted on the handle and adapted to project below the lower end thereof, the adjacent head member having a row of sockets therein concentric to the stud and into which sockets said pin is adapted to selectively engage, and means to advance said pin into one of said sockets and to maintain the pin so advanced.

10 2. A safety razor comprising a pair of cooperating head members adapted to clamp a double-edged blade therebetween, a central, threaded stud on one member projecting through the other member, a handle screwed onto said stud whereby to secure said members together and clampingly engage the blade therebetween, a pin slidably extending longitudinally through the handle from end to end thereof, means on the handle tending to retract said pin relative to the lower end of the handle, and means on the handle manually operative to cause projection of said pin from said lower end of the handle; the adjacent head member having a row of sockets concentric to the stud; the pin when advanced and projecting from the lower end of the handle being adapted to engage selectively in one of said sockets whereby to lock the handle against rotation relative to the stud.

30 3. A device as in claim 2 in which said first named means comprises a spring, and said last named means comprises a screw cap threaded on the outer end of the handle and engaging the adjacent end of the pin.

4. A device as in claim 2 in which said first named means comprises a compression spring surrounding the pin within the handle and engaged between a shoulder on the pin and a shoulder in said handle; said last named means comprising a screw cap threaded on the outer end of the handle and engaging the adjacent end of the pin.
